The ornamental design for protective goggles, as shown and described.

DESCRIPTION

FIG. 1 is a perspective view from the front and slightly above of the protective goggles in accordance with the present invention;

FIG. 2 is a top plan view thereof more clearly displaying two side pieces of the protective goggles which extend backwardly in the direction of the user's face from their upper rim; and,

FIG. 3 is an elevational view from the left side thereof, the right side elevational view being a mirror image thereof.

FIG. 1

FIG. 2

FIG. 3
